MARTIN FOX, OF CHICAGO, ILLINOIS, ASSIGNOR TO THE SENG COMPANY, OF CHICAGO, ILLINOIS, A CORPORATION OF ILLINOIS.

CORNER LOCK.

Application filed September 24, 1923. Serial No. 664,339.

This invention relates to a locking device for steel rails used particularly in connection with beds, but may have a more general use wherever applicable. The principal object 5 of the invention is to provide a new and improved construction, combination, and arrangement of the parts whereby an angle bar may be held either in the ordinary or the inverted position by use of the same fastening device. Another object of the invention is 10 to make a receiving box or housing of a single piece of sheet material which is simple, strong, and inexpensive.

In the accompanying drawings, Fig. 1 is 15 a front view of a corner lock constructed in accordance with the principles of this invention showing a rail in one position; Fig. 2 is a similar view showing the rail in inverted position; Figs. 3 and 4 are side and top views of 20 the corner lock respectively; Fig. 5 is a section taken on the line 5—5 of Fig. 3; Fig. 6 is a perspective of the wedging or locking member; Figs. 7, 8 and 9 are front, side, and top 25 views respectively of a modified form having a different wedging member; Fig. 10 is a section taken on the line 10—10 of Fig. 8; Fig. 11 illustrates a corner lock with oppositely disposed wedging members; and Fig. 12 is a section taken on the line 12—12 of Fig. 11 30 further illustrating this modified form.

In the wedging member type of corner lock it is difficult to provide a single wedging member which will engage an angle bar rail both in the normal and in the inverted position. 35 To provide a wedging member for engaging such a rail in one position or the other it is relatively simple, but to accommodate different widths of springs it is desirable that the side rails can be inverted. The present invention 40 accomplishes this result in a very simple manner and provides means for preventing the angle bar from becoming displaced and thereby improperly wedged in the housing.

In carrying out this invention, a box or housing 1 is formed up out of a single sheet of metal meant to form a rectangular housing 2, one extremity of which has reduced tongues 3 inserted through perforations in the other 45 extremity, and the heads 4 of these tongues are battered or riveted to form a closed box. At the edges of these adjoining extremities are 50 perforated tabs 5 and 6 at right angles to each other to which a cross connecting bar 7 is

connected by bolts or rivets 8. Extending 55 oppositely from the lower and upper sides of the box are attaching ears 9 and 10 through which bolts or screws 11 are inserted for fastening the corner lock to a post 12.

One side of the box is formed with a perforated raised portion or offset 13 through which a bolt 14 is inserted, and the opposite side of the box is provided with an opening 15 preferably rectangular in shape to receive the corresponding end of a locking member 16. The locking member 16, as shown more 60 clearly in Fig. 6, is also formed up out of sheet material and comprises similar wedging sides 17 and opposite perforated ends 18. On the edge of each side 17 are wedging surfaces 19 and 20 spaced apart approximately the thickness of the box 2.

This wedging member 16 is placed on the bolt 14 and inserted within the box 2 where it is held in position by the rectangular opening 15. A washer 21 and a thumb screw 22 are then placed upon the threaded end of the bolt so that the wedging member may be drawn up tightly thereon and the corner lock 70 is ready for use.

If an angle bar side rail 23 is inserted in the regular position, as shown by Fig. 1, one edge of the bar is engaged by the wedging edges 19 of the member 16 and if the side rail 23 is inverted, as shown by Fig. 2, the other edge of the side rail is engaged by other wedging surfaces 20 of the locking member 16. In this form of the invention, an inwardly turned wing 24 may be provided for holding the side rail 23 in its ordinary position, 80 as shown in Fig. 7, but the wedging surfaces 19 will hold the side rail in upright position unless it fits too loosely in the box 2.

In the form of invention shown by Figs. 7 to 10 the box or housing 25 is similar to that already described with the exception that there are opposite rectangular openings 26 and 27 for receiving a wedging member 28 which can be driven in place against a side rail 23 in regular or inverted position. The 90 smaller end of the wedging member 28 is formed with a lip 29 which prevents it from becoming disengaged from the box 25.

In the form of the invention shown by Figs. 11 and 12, a box or housing 30 similar to that 100 already described is formed with an offset portion 31 with an opening 32 for seating a circular wedging member 33 adapted to be

placed upon a bolt 14 with its larger end against the head thereof. Another similar wedging member 33 is placed at the opposite end of the bolt and the two wedging members 5 are separated by a spring 34 which tends to press them apart. At the bottom of the box 30 is an opening 35 in which the lower wedging member fits loosely, and a washer 21 and a wing nut 22 are placed on the threaded end 10 of the bolt to draw the wedging members 33 up tightly. One or the other of the wedging members engages the corresponding edge of a side rail 23 placed in the box 30 in regular or inverted position.

15 In all of these constructions it is obvious that the side rail is held tightly in the box and if it is loosened because of variation in size of the different parts, the side rail may be tightened in place. Furthermore the side rail will be held securely either in regular 20 or in the inverted position.

I claim:

1. In a corner lock, a rectangular housing adapted to be attached to a post and with opposite 25 perforations therein, wedging means including a bolt and a member mounted in the perforations and the member being movable relatively to the housing, the said wedging member being adapted to engage either 30 one edge or the other of a plain angle bar inserted in the housing at one side thereof in normal or in inverted position.

2. In a corner lock, the combination with a rectangular housing having opposite perforations 35 therein, of an unnotched angle bar side rail inserted in the housing in regular or in inverted position, and wedging means

including a bolt and a wedging member operating in the perforations of the housing for engaging one edge or the other of the side 40 rail depending upon its position in the housing.

3. In a corner lock, a rectangular housing having opposite perforations therein, a wedging member movable in one of the perforations, a bolt inserted through an opposite perforation and upon which the wedging member is mounted, and threaded means at the end of the bolt for operating the wedging member. 50

4. In a corner lock, a rectangular housing, a bolt extending transversely through the housing with the head engaging one side thereof, a wedging member movable on the bolt and through the wall of the housing, 55 and means at the end of the bolt for effecting the wedging action of the member.

5. In a corner lock, a rectangular housing, a wedging member movable therein, said member comprising opposite sides each having spaced wedging surfaces, and means upon which the member is mounted for moving it operatively through the wall of and in the housing to effect a wedging action. 60

6. In a corner lock, a housing having perforations in opposite walls, a wedging member movable in the housing and through one wall thereof having opposite edges with wedging surfaces thereon and perforated 70 ends, a bolt extending through the perforated ends and mounted in the housing, and means on the bolt for effecting the wedging movement of the member thereon.

MARTIN FOX.
